Dawn. 10th

Attorney.

UNITED STATES PATENT OFFICE.

FRANK M. LEE, OF CHICAGO, ILLINOIS, ASSIGNOR TO SULLIVAN MACHINERY COMPANY, A CORPORATION OF MASSACHUSETTS.

DRILL-SHARPENING MECHANISM.

Application filed January 5, 1923. Serial No. 610,929.

My invention relates to drill sharpening mechanisms, and more particularly to devices for the purpose of opening the holes through which cleansing fluid is supplied in 5 the case of drill steels.

An object of my invention is to provide an improved hole opening or "pinning out" mechanism. Another object of my invention is to provide an improved pinning out 10 mechanism of a type in which the pinning tool is fed by power toward and from the work. A further object of my invention is to provide an improved pinning mechanism of the percussive type in which the pinning 15 tool may be positively fed into the work and positively retracted while being hammered to facilitate its withdrawal. Other objects and advantages of my invention will hereinafter more fully appear.

20 In the accompanying drawings I have shown for purposes of illustration one form which my invention may assume in practice.

In these drawings,—

The figure is a view partially in side elevation and partially in central longitudinal vertical section through the illustrative embodiment of my invention.

In this embodiment of my invention I have shown the same mounted upon a frame 30 1 which provides a table 2 at its upper side. Upon the table 2 is secured a combined pinning out motor and feeding mechanism, generally designated 3 and comprising a cylinder 4 having herein opposite heads 5 and 6 35 each of which provides a guiding means as at 7 and 8 for piston rod portions 9 and 10. The latter are fixed to a member 12 within the cylinder 4, which member constitutes a piston for the cylinder 4 and houses a motor 40 for actuating a pinning tool 13. It will be noted that the member 12 is bored out as indicated at 14 to form a cylinder in which a piston 15 is reciprocable under the influence 45 of air admitted through an inlet port 16 and distributed by a groove 17 in the piston to bypass passages 18 and 19 leading to the opposite ends of the cylinder 14. For the purpose of supplying fluid to the inlet port 16, I provide a passageway 21 extending 50 throughout the length of the cylinder member 12 and arrange at each end of the passage 21 an inwardly opening check valve 22 which permits the admission of fluid,

but prevents the discharge of fluid from within. It will be noted that suitable exhaust ports 24 are arranged in the walls of the cylinder 12 and these are connected to a passage 25 which opens through a port 26 in the cover 5 to the atmosphere. Passages 27 and 28 leading to the ends of the cylinder 14 are controlled by a manually operable control valve 29 through whose bore 30 fluid may be supplied alternately to the passages 27 and 28. A suitable manual operating lever 31 controls the operation of the valve. A groove 32 serves alternately to connect either the passage 27 or 28 with an atmospheric vent 33. It will be noted that the exhaust need not take place in the manner specified as the exhaust could also 70 take place through the ends of the member 12 and pass by way of whichever passage 27 or 28 was then open to the atmosphere, it being understood that outwardly opening check valves would have to be located in such a passage. A spring held tool retainer 35 is arranged to always hold the pin 13 within the reach of the piston 15 so that even during retraction of the pin the same may still be hammered, even during withdrawal. A suitable vise 36 is arranged to support a drill steel during the pinning out operation. A steel is shown at 37 in this vise.

The mode of operation of my invention as 85 illustrated herein is as follows: Assume that a steel has been arranged within the vise 36 as shown at 37. The air supply to the valve 29 having been turned on, the latter will be turned by means of the handle 31 to a 90 position in which the port 30 will communicate with the passage 28, while the passage 27 will be connected by the groove 32 to the exhaust 33. Air will accordingly pass to the rear end of the cylinder 4 and tend to force the piston 12 toward the left. Simultaneously a portion of the air will unseat the right hand valve 22 and pass through the passage 21 to the port 16, the other valve 22 being then held closed by air pressure. From the inlet port 16 the groove 17 will 100 distribute the fluid to the passages 18 and 19 to effect hammering operation of the piston 15 and the exhaust fluid will flow through the ports 24, passage 25 and port 26 to the 105 atmosphere. When the penetration of the

pin 13 is sufficient, the lever 31 will be operated to reverse the position of the valve 29 and air will then be supplied to the front end of the cylinder 4, while the rear end 5 of the cylinder 4 will be connected to the exhaust. Air will then pass the other valve 22 and operate the motor during retraction, the vibration of the steel by hammering during retraction greatly facilitating the withdrawal 10 of the pin. When the pin has been fully withdrawn, the air will be shut off from the valve 29 by any suitable means (not shown).

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In a hole opening punching mechanism, 25 a feed cylinder, a motor disposed within said feed cylinder and including a punch operating piston, and means for supplying fluid pressure to the last mentioned motor including a passage extending from end 30 to end thereof and controlled by a check valve at either end.

2. In a hole opening punching mechanism, 35 a support for a drill steel, a stationary feed cylinder arranged adjacent said support, a pin operating motor reciprocable relative to said feed cylinder and drawing its fluid supply in alternation from the opposite ends of said feed cylinder, and means operative to continually maintain the pin within the action 40 of said motor during retraction.

3. A drill steel punching mechanism comprising a punch, a percussive motor for actuating the same, pressure fluid means for feeding and retracting said motor including 45 a double acting cylinder and piston mechanism one of whose elements is movable with the percussive motor, and means for supplying pressure fluid to said double acting cylinder and piston mechanism to effect opposite feeding movements, said element movable with the percussive motor being traversed completely by a passage connected between its ends with the percussive motor and having a check valve therein at each side of the connection with the percussive motor.

4. In a hole opening punching mechanism, 60 a support for a drill steel, a pneumatic feeding mechanism arranged adjacent thereto, a pin operating motor reciprocable relative to said feeding mechanism, said feeding mechanism including a cylinder surrounding said motor, and means including a common valve and common supply passages for supplying operating fluid from said valve to said motor 65 and to either of the opposite ends of said

cylinder to effect reciprocation of said motor and operation thereof during feed in either direction.

5. In a hole opening punching mechanism, 70 a support for a drill steel, a pneumatic feeding mechanism arranged adjacent thereto, a pin operating motor reciprocable relative to said feeding mechanism, said feeding mechanism including a cylinder surrounding said motor, and means including a common valve 75 and common supply passages for supplying operating fluid from said valve to said motor and to either of the opposite ends of said cylinder to effect reciprocation of said motor and operation thereof during feed in either direction, the fluid flowing from said feed cylinder to said motor.

6. In a hole forming mechanism, a tool, 80 a percussive motor adapted to actuate said tool, fluid pressure means for feeding said motor in opposite directions including a cylinder surrounding said motor, and means to admit pressure fluid from said feeding means to operate said motor in either direction of feed.

7. In a hole forming mechanism, a tool, 85 a percussive motor adapted to actuate said tool, means for feeding said motor in opposite directions, and means to admit pressure fluid to said motor from only the operating end of said feeding means during operation thereof during both feeding movements.

8. In a hole forming mechanism, a punch, 90 a percussive motor for actuating the same, pressure fluid feeding means for said motor, 100 and means including yieldable valve mechanism carried by said motor permitting admission of fluid from the feeding means to said motor.

9. A hole forming mechanism comprising 105 a tool, a percussive motor adapted to actuate the same, means whereby opposite ends of said motor may be subjected to pressure fluid to feed the same, and means whereby actuating fluid for said motor is supplied thereto from one or the other of said ends automatically in accordance with the direction of motor feed.

10. A hole forming mechanism comprising 110 a tool, a fluid actuated percussive motor for actuating the same, a feed cylinder, a base therefor having a passage associated therewith and leading to the opposite ends of said cylinder, a manually operable valve for controlling fluid flow alternatively to said ends, 115 and a valve controlled passage in said motor operative automatically to allow flow of pressure fluid from only one or the other of said ends to said motor in accordance with the existence of pressure fluid in either of said ends.

11. In a hole forming mechanism, a percussive motor adapted to actuate a pin, pressure fluid feeding means therefor, and means including automatically operative spring 120

pressed valves for supplying pressure fluid from said feeding means to operate said motor.

12. In a hole opening mechanism, a feed cylinder, a piston movable therein, a percussive motor carried by said piston, means for supplying pressure fluid to said feed cylinder, and means for supplying pressure fluid to said motor including ports leading to the opposite ends of said feed cylinder, and alternatively operative check valves.

13. In a hole opening mechanism, a pin, a pressure fluid actuated percussive motor adapted to actuate said pin, pressure fluid actuated feeding means therefor, means for supplying pressure fluid to said motor, and

means disposed coaxially with said motor at the rear end thereof for exhausting pressure fluid from said motor.

14. In a hole opening mechanism, a pin, 20 a pressure fluid actuated percussive motor adapted to actuate said pin, pressure fluid actuated feeding means therefor, means for supplying pressure fluid to said motor selectively through the opposite ends thereof 25 to effect operation thereof in either direction of feed, and means disposed coaxially with said motor for exhausting fluid from both ends of said motor.

In testimony whereof I affix my signature.

FRANK M. LEE.
